GARMENT HANGER

Carl E. Gingher, 304-328 Depot St.,
Scranton, Pa. 18509

Filed Dec. 9, 1968, Ser. No. 14,853

Term of patent 14 years

Int. Cl. D6—07

U.S. Cl. D80—8

FIG. 1 is a perspective view of a garment hanger showing my new design;

FIG. 2 is a side elevational view thereof;

FIG. 3 is a top plan view thereof;

FIG. 4 is an end elevational view thereof; and

FIG. 5 is a fragmentary cross sectional view taken on line 5—5 of FIG. 2, the center of the garment hanger being broken away for convenience of illustration.

The essential feature of my design resides in the combination of the support stem with the hanger body.

I claim:

The ornamental design for a garment hanger, as shown and described.
